CLAIM

The ornamental design for a notebook computer with detachable keyboard, as shown and described.

DESCRIPTION

FIG. 1 is a front, right side and top perspective view of a notebook computer with detachable keyboard showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, left side and top perspective view thereof;

FIG. 9 is a front, left side and bottom perspective view thereof;

FIG. 10 is a front, right side and bottom perspective view thereof;

FIG. 11 is a front, right side and top perspective view thereof showing a keyboard assembled with the notebook computer;

FIG. 12 is a front, left side and top perspective view thereof;

FIG. 13 is an enlarged view of the portion indicated in FIG.

11;

FIG. 14 is an enlarged view of the portion indicated in FIG.

11;

FIG. 15 is an enlarged view of the portion indicated in FIG.

11;

FIG. 16 is an enlarged view of the portion indicated in FIG.

12;

FIG. 17 is an enlarged view of the portion indicated in FIG.

12; and,

FIG. 18 is an enlarged view of the portion indicated in FIG.

12.

The ornamental design which is claimed is shown in the drawings as solid lines and surfaces having surface shading. The dashed broken lines are for the purpose of depicting environment and form no part of the claim design. The dot-dash broken lines define the bounds of the claimed design and form no part thereof.
